(57) **CLAIM**

The ornamental design for a bottle, as shown and described.

DESCRIPTION

FIG. 1 is a left side elevation view of a bottle in accordance with our design;

FIG. 2 is a right side elevation view thereof;

FIG. 3 is top plan view thereof;

FIG. 4 is a bottom plan view thereof.

FIG. 5 is a perspective front elevation view thereof; and,
FIG. 6 is a perspective rear elevation view thereof.

The broken line showing of the bottle neck is for illustrative purposes only and forms no part of the claimed design.
